METHOD AND MACHINE FOR MAKING VULCANIZED FIBER.

Application filed May 24, 1927. Serial No. 193,755.

This invention relates to a method and means for manufacturing a product ordinarily known as "fiber" through plying and vulcanization of fibrous sheet or web material such as paper. In machines heretofore designed for this purpose, the fibrous base material-paper, after having been run through a bath of vulcanizing solution, was continuously built or plied upon a revolving cylindric mandrel until the desired thickness was obtained in the product. Thereupon, the "fiber" was cut from the mandrel; and in order to convert it into a flat sheet, had to be subjected to very high pressures—usually applied by hydraulic means—for removal of the curl inherent in it as a consequence of having been formed on the cylindric surface of the mandrel. The flattening treatment just referred to caused severe strain on the fibers, often resulting either in transverse fracture, longitudinal splitting or separation between plies or layers, or buckling of the product, these tendencies obviously becoming more pronounced with increase in the thickness.

The object of my invention is to overcome the difficulties above pointed out: in other words, I aim to enable direct manufacture of the fiber, i. e. without necessitating subsequent flattening, and to provide a very simple and reliable apparatus whereby this may be continuously and expeditiously accomplished.

In the drawings, Fig. I is a side elevation of a fiber making machine conveniently embodying my invention.

Fig. II is an elevation of the machine, as viewed from the left hand end of Fig. I, with portions broken away and in section in accordance with the arrows II—II in the latter figure.

Fig. III is a longitudinal sectional view of the structure; and

Fig. IV is a diagrammatic view showing successive positions of the mandrel upon which the fiber is built.

With reference first more particularly to Figs. I and III of these illustrations, it will be observed that the fibrous web W which is to constitute the base for the product to be manufactured, is drawn from a supply roll 10 which is supported for free rotation between bearing standards 11 afforded by the side frames 12, 12 of the machine at one end. From the supply roll 10 the web W passes

to a vat 13 supported at a higher elevation by laterally projecting arms 14 of the side frames 12, said vat containing a suitable vulcanizing solution such as ordinarily employed in this art. A series of guide rollers 15, 16 and 17, serve to insure travel of the web W immersed in the solution; and a pair of directional rolls 18, 19 cooperate through impartation of a slight drag or tension, to remove the excess solution from the web as it leaves the vat. The rollers 16—19 are all carried by a frame 20 having pivotal connection for upward swinging about the axis of the roller 15 for convenience in initially threading the web W in the machine. The now saturated web W proceeds over a transverse guide roller 21 with journal bearings in the side frames 12, 12, and then about and under a weighted pressure roller 22 resting upon the winding mandrel 23. This mandrel 23 has flat side faces, and in the present instance is hollow and square in cross section. A pair of arms 24, 24 pivotally suspended from a transverse shaft 25 extending between the side frames 12, 12 of the machine at the top, are slotted at their lower ends to engage trunnions 26, 26 projecting axially from opposite ends of the mandrel 23. These arms 24 serve to move the mandrel 23 back and forth, swinging movement being imparted to said arms 24 by virtue of slotted engagement with rollers 28 eccentrically mounted on discs 29 which revolve in openings 30 in the side frames 12, see Figs. II and III. Affixed to the discs 29 are worm wheels 31 which are enclosed in housings 32 secured exteriorly of the side frames 12 and driven by worms 33 (Fig. I) at the lower ends of vertical shafts 34. The shafts 34 are in turn driven through bevel gear couples 35 from a horizontal shaft 36 journalled in appropriate bearings 37 on a horizontal bridging member 38 connecting the side frames 12, 12 of the machine at the top. At its middle, the shaft 36 carries a worm wheel 39 arranged to be driven, at reduced speed, by a worm 40 on the shaft of an electric motor 41 which is also mounted on the bridging member 38.

At all of its eight corners the mandrel 23 is equipped with rollers 42 adapted to ride on horizontal tracks 43 projecting inward from the opposite side frames 12, 12 so as to define horizontal travel of said mandrel under the action of the arms 24 in moving

- forward to the right from the full line position in Fig. IV. The mandrel 23 is further equipped at all eight corners with cupped lugs 44, whereof the rearmost ones at the top are adapted, incidental to movement of the mandrel 23 toward the right, to engage fixed stops 45 that project inward from plates 46 bolted to the in-sides of the machine frames 12, 12, see Figs. II and III.
- 10 As the mandrel 23 reaches the forward limit of its horizontal movement in the direction just referred to concurrently with the engagement of the cupped lugs 44 with the fixed fulcrum stops 45, the rollers 42 at that time at the lower right hand corners drop from the tracks 43—as shown in dotted lines in Fig. IV—and onto auxiliary curved tracks 47 having their centers of curvature co-incident with the stops 45, so that during rearward movement of the arms 24, said mandrel is obliged to swing about the fulcrum stops 45—as indicated in dot and dash lines in Fig. IV, being thereby caused to turn through an angle of ninety degrees before it
- 15 20 again assumes the full line position in the illustration last mentioned. During the latter part of the return movement of the mandrel 23 toward the left, the rollers 42 riding on the curved tracks 47 encounter a pair of 25 spring urged arms 48, forcing them rearward until engaged in the shoulders 49 of said arms, as shown in full lines in Fig. IV. Upon initiation of the next forward movement of the mandrel 23 toward the right, 30 the arms 48 serve, with the assistance of helical tension springs 50 to which they are subject, to lift the rear lower corner rollers 42 to the level of the straight tracks 43.
- In order to permit free up and down movement of the roll 22 to insure uniform application of pressure and to accommodate the turning of the mandrel 23 corners beneath it, its shaft ends are mounted in journal blocks 51 guided in vertical slots of the plates 46 previously referred to.
- 35 From Figs. III and IV it will be noted that the trunnions 26 of the mandrel 23 are tubular for capacity to serve as passages for introduction and exhaust of steam or other 40 heating medium into the follow interior of said mandrel. Flexible steam supply and exhaust tubes or conduits 53, 54 are connected to the trunnions 26 by swivel couplings 55 so as not to interfere with or retard movements of the mandrel 23, see Fig. 45 II. Any other suitable means may be employed for maintaining the mandrel 23 heated to expedite vulcanization of the fiber.
- In the operation of the machine, as the 50 mandrel 23 moves to the right in Figs. III and IV, it is confined to horizontal travel by the straight tracks 43, and as a consequence, its upper face is progressed in true parallel relation along a straight line beneath the floating pressure roll 22. This roll
- 55 60 65 70 75 80 85 90 95 100 105 110 115 120 125 130
- 22 in following the dictates of the mandrel 23 is obliged to revolve thus drawing upon the web W to lay and at the same time press it on the top face of said mandrel. After having reached the limit of its movement toward the right, the mandrel 23 is turned clockwise, as previously explained, through a quadrant about the corner angle at that time beneath the roll 22, with consequent presentation to the latter, of the succeeding face for repetition of the laying and rolling operation described above. Such rotation of the mandrel occurs after each forward pass so that the operation is continuous, the draft upon the web W being uniform except perhaps for the interval consumed in rounding corners. After the operation has been carried on to the desired extent, the fiber is cut along the corner edges of the mandrel 23 and removed in sheets that are perfectly flat, entirely devoid of surface or internal imperfections and in a completely finished condition. It is to be particularly noted that by horizontal passage of the mandrel faces successively beneath the weighted roll 22, the plies are subjected to uniform pressure incidental to application of the fibrous base web W so that the plies are firmly compacted to a uniform thickness throughout the extent of said faces.
- Having thus described my invention, I claim:
1. A fiber making machine comprising a mandrel with flat side faces, a cooperating floating pressure roll, and means to move the mandrel back and forth for passage of its upper face horizontally beneath the pressure roll, and means to rotate the mandrel at intervals for successive presentation of its faces to the pressure roll.
  2. A fiber making machine comprising a mandrel with flat side faces, a cooperating floating pressure roll, means to move the mandrel back and forth for passage of its top face horizontally beneath the pressure roll, and means to rotate the mandrel after each such pass for presentation of a succeeding face to the pressure roll.
  3. A fiber making machine comprising a mandrel with flat side faces, a cooperating floating pressure roll, means to move the mandrel back and forth for passage of its top face horizontally beneath the pressure roll, and means to rotate the mandrel about an upper corner angle as an axis after each such pass for presentation of a succeeding face to the pressure roll.
  4. A fiber making machine comprising a mandrel with flat side faces, a cooperating floating pressure roll, means to move the mandrel back and forth relative to the pressure roll, means to determine horizontal travel of the mandrel when moving in one direction for passage of its upper face in a straight line beneath the pressure roll, and

In testimony whereof, I have hereunto signed my name at Philadelphia, Pennsylvania, this 18th day of May, 1927.

GEORGE W. TEMPLE.
